FENCE SECTION

John S. Case, Towson, Md., assignor to Anchor Post Products, Inc., Baltimore, Md., a corporation of New Jersey

Filed Mar. 15, 1962, Ser. No. 69,275

Term of patent 14 years

(Cl. D28—1)

FIG. 1 is a front perspective view of a fence section showing my new design; and

FIG. 2 is a fragmentary perspective view of one of the louvered panels of the section shown in FIG. 1.

The opposite side of the fence is substantially the same in appearance as the front side of the fence section as shown in FIG. 1.

I claim:

The ornamental design for a fence section, as shown and described,
